SAFETY RAZOR AND BLADE

Meyer J. Shnitzler, Jamaica Plain, Mass., assignor
to Gillette Safety Razor Company, Boston,
Mass., a corporation of Delaware

Application September 12, 1944, Serial No. 553,679

9 Claims. (Cl. 30—70)

The present invention consists in a new and improved blade for safety razors of the type employing cooperating blade-clamping members for supporting a thin flexible blade in position for shaving. Two general types of such safety razors are now commonly used; one in which the two clamping members of the razor are detachable and may be entirely separated for the removal or presentation of the blade, and the other in which the clamping members are not detachable but are arranged for a limited separation only in order to provide passage in which the blade may be presented endwise between them. With the latter type of safety razor it is necessary to employ an open-end blade; that is to say, a blade having its two sharpened side portions separated by a medial longitudinal slot opening out through one of its unsharpened ends.

The principal object of the present invention is to provide a thin, flexible safety razor blade of such construction that it may be manufactured and distributed to the user as a closed-end blade and yet may be used with equal facility in razors of either of the types above described. In this sense the blade of my invention may be termed a dual-purpose blade. The blade of my invention serves equally well in both relationships. It is capable of manufacture conveniently under existing commercial conditions; that is to say, it compares favorably with a closed-end blade in the facility of the manufacturing steps by which it is produced. It is entirely convenient for the user in that its transformation into an open-end blade requires no effort or attention on the part of the user but is effected in the usual steps of withdrawing the blade from its magazine or of presenting it to the safety razor.

I have discovered that these and other advantages may be secured by providing a breakable tie, connecting link or bridge between the two side portions of the blade at one or both ends and providing cooperating means either in the magazine or in the razor itself for breaking out this tie in the step of presenting the blade to the razor. The tie may be so located in the blade that it does not in any way interfere with presentation of the blade to a safety razor in which the two clamping members are fully separated for the reception of a fresh blade. During the manufacturing process moreover the tie maintains the blade as a self-contained unit, preventing any spreading or distortion of the side portions of the blade at its free end and maintaining the blade in this self-contained condition up

to the very time of its presentation for shaving in the safety razor.

The particular shape of the tie is of secondary importance so long as it fulfills the requirements above outlined. If the razor contains an elongated blade-locating rib, the blade is correspondingly slotted and it is important to provide an unobstructed passage to this slot when the tie is broken out of the blade. This is true because if the passage were to be interrupted by ragged fragments of the tie left in the blade it could not be passed over the blade-locating rib. With that end in view, an important feature of the invention consists in providing the blade slot with a terminal enlargement, wider than the blade slot and in so arranging the tie that it is greater in length from side to side than the width of the slot. Accordingly, when the tie is broken out of the blade it removes with it an area providing free and unobstructed approach to the end of the blade slot.

A preferred manner of effecting the desired results is to notch the unsharpened end portion of the blade by notches forming a tongue with side edges diverging or spreading apart to points wider than the blade slot. Here the tongue may merge into the transverse tie and may afford convenient means for breaking the tie out of the blade by a twisting movement requiring a minimum of force to effect the desired results.

Another beneficial result of this blade construction is that it renders possible the employment of a safety razor in which the clamping operation may be effected from a central point without wholly separating the clamping members for the presentation of the blade.

These and other features of the invention will be best understood and appreciated from the following description of a preferred embodiment 40 thereof selected for purposes of illustration and shown in the accompanying drawing in which:

Fig. 1 is a view in perspective on an enlarged scale of the head of a safety razor showing a blade as being presented thereto;

Fig. 2 is a similar view of the blade alone;

Fig. 3 is a fragmentary view in perspective showing the end of the blade with the tie removed;

Fig. 4 is a plan view on a still larger scale showing one end of the blade;

Fig. 5 is a view in longitudinal section corresponding to Fig. 1; and

Fig. 6 is a detailed top plan view of a spring element shown in Figs. 1 and 5.

The invention as herein shown is embodied in

a blade of the well-known "Gillette" type although it is not limited in its application to that or to any specific type of blade but with appropriate modifications may be embodied with advantage in any slotted blade.

The blade herein shown is formed of thin flexible sheet steel .003 to .007 inch, or thereabouts, in thickness. It comprises two sharpened side portions 10 of complementary shape with sharpened longitudinal edges 11. The side portions of the blade are partially separated by a longitudinal medial slot 12 terminating at both ends in a transverse enlargement substantially wider than the slot and having a curved transverse end edge. As herein shown, the blade is provided also with a pair of intermediate diamond-shaped enlargements and with a circular central enlargement to fit and receive blade-locating projections and the cap spindle of the razor with which the blade is to be used. Preferably and as herein shown, the walls 15 of the slot which connect the terminal enlargement 13 with the intermediate enlargement 14, and the rest of the slot, diverge toward the end of the blade and are utilized as guiding edges for centering the blade when the latter is presented to the razor as will presently appear.

The blade is provided in each of its corners with a reentrant notch and these notches define elongated unsharpened end portions 16 and 17 in the blade. These end portions, or one of them, constitute flexing hinges when the blade is clamped in transversely curved position for shaving in the razor. As herein shown, one end portion 16 only is modified for purposes of the present invention; the other 17 being left in its usual shape.

Centrally disposed in the end 16, however, is a tongue 18 defined by end notches 19 and 20. The outer walls of these notches are spaced apart a greater distance than the width of the slot 12, these dimensions being indicated in Fig. 4 by reference characters A and B and the relationship exists $A > B$. The inner walls of the notches 19 and 20 flare outwardly and the base of the tongue 18 merges into the tie or bridge portion 21 the inner edge of which is formed by the transverse terminal enlargement 13. It will thus be seen that the tie 21, much reduced in thickness at its ends by the shape of the notches 19 and 20, is the only connection in the end 16 between the two side portions of the blade. The blade is given this characteristic shape in order to provide a fragile, easily breakable tie that can be removed by the application of slight force and when so removed will provide an unobstructed opening into the slot 12 which is at least as wide as the slot itself and which will thus permit the presentation of a rib or other projection having the full width of the slot.

Having provided a fragile tie in this manner, provision is made for easily removing it by forming the tie integrally with the tongue 18 which extends longitudinally into the space provided by the notches 19 and 20. Accordingly when the tongue is twisted in either direction out of the plane of the blade the tie 21 is snapped off and broken out of the blade along two lines running into the enlargement 13. These lines of fracture generally converge slightly as clearly shown in Fig. 3 so that the opening formed in the end of the blade is slightly contracted at the outer edge of the enlargement 13. However, since the outer edges of the notches 19 and 20 are substantially wider than the blade slot 12 the points or fangs remaining in the blade will always be

spaced more widely apart than the width of the blade slot and the effective opening thus provided will permit the entrance of a rib of the full width of the slot.

The tongue 18 may be twisted to break the tie 21 by means available either in the razor or in the magazine but as herein shown the safety razor is equipped with a tie removing device. The razor illustrated in Figs. 1 and 5 comprises a guard member 22 secured to the upper end of the handle 23 and a cooperating cap member 24. The blade supporting face of the guard member is generally convex in transverse contour and the inner face of the cap 24 is correspondingly concave so that when the blade is clamped between them it has imparted to it a substantial transverse curvature.

To the upper face of the guard is attached a forked-leaf spring 25 (see also Fig. 6) which extends the full length of the guard member. It is centrally perforated to afford free passage for the cap spindle 26 and slightly separated at its side edges from the upper surface of the guard. It serves as a blade-locating and retaining device in the razor when an open-end blade is slipped endwise beneath its edges. Its forked ends are slightly flared upwardly to facilitate entrance of the blade and the end edges of the guard are correspondingly beveled for the same purpose.

Corner studs 27 project downwardly from each corner of the cap and are received in corresponding recesses provided for that purpose in the body of the guard 22. The locating studs 27 engage the shoulders of the elongated end portions 16 and 17 of the blade, thus not only locating the blade transversely of the razor but positively preventing distortion by spreading of the side portions 10 at the open end of the blade.

The guard is cut away centrally near each end for the reception of a breaking device constructed and arranged to engage the tongue 18 and break out the tie 21 by a twisting movement when a blade is presented to the razor as suggested in Fig. 5 of the drawing. This tie-breaking device comprises a flat plate 28 from which rises a rib 29 having a downwardly and rearwardly inclined edge face 30. The rib 29 extends upwardly, slightly above the surface of the guard and substantially flush with the forked ends of the retaining spring 25. The device is held in position by a screw 31 passing through the plate 28 and threaded into the body of the guard 22. The retaining spring 25 is secured in place by rivets 32 passing into the body of the guard.

From the foregoing description it will be apparent that when a blade of the construction illustrated in Figs. 1-4 is presented to either end of the razor by hand or from a magazine the end of the blade 16 moves inwardly along the surface of the guard 22 while the tongue 18 encounters the inclined edge 30 of the rib 29 and is deflected downwardly by it. As the blade is pressed inwardly the tongue 18 is deflected or twisted downwardly more and more until finally the tie 21 is broken away from the end of the blade and a passage opened into the end of the slot 12 through the diverging edges 15 above referred to. When this happens, the blade is free to be advanced fully into shaving position. It is kept centrally in alignment by the rib 28 which fills the blade slot 12 and it is arrested in the proper longitudinal position by the engagement of the inclined wall of the rib 29 with the inside edge 75 of the slotted end 17 of the blade. This locates

the blade with the cap studs 27 properly registering with the end notches in the blade. Accordingly the cap may now be drawn downwardly into blade-clamping position by a screw-threaded connection (not shown) with the cap spindle 26.

Having thus disclosed my invention and described in detail an illustrative embodiment thereof, I claim as new and desire to secure by Letters Patent:

1. A safety razor blade comprising two sharpened side portions separated by a longitudinal slot terminating in an enlargement at one end which is wider than the blade slot, and a breakable tie closing the slot beyond the said enlargement and having side edges defined by notches that spread wider than said slot.

2. A safety razor blade comprising two sharpened side portions separated by a longitudinal slot terminating in an enlargement, a tongue defined by parallel notches in the end of the blade, and a breakable tie into which the tongue merges and which is longer from end to end than the width of the slot.

3. A safety razor blade comprising sharpened side portions, separated by a longitudinal slot having a terminal enlargement, a tongue projecting outwardly in line with said slot, and a breakable tie connected to said tongue and being itself connected to the side portions of the blade at points more widely separated than are the edges of the said blade slot; whereby an unobstructed passage to the slot is opened when the tie is broken.

4. A safety razor blade comprising two sharpened side portions separated by a longitudinal slot terminating in a curved enlargement at one end which is wider than the blade slot, and a breakable tongue closing the slot beyond said enlargement.

5. A double edged blade for a safety razor, having corner notches defining elongated unsharpened end portions and a longitudinal slot extending into said end portions, a tongue in one of said

end portions defined by spaced end notches, and a tie extending transversely between the inner ends of said notches and across the end of said longitudinal slot.

6. A double edged blade for a safety razor, having sharpened edge portions partially separated by a longitudinal medial slot transversely widened at its end, an unsharpened end portion, a transverse tie joining the side portions adjacent to and beyond the widened end of the said slot, and a tongue in the end portion merging inwardly into said tie and having side edges that diverge outwardly to width greater than the slot, whereby an unobstructed passage is opened when the tie is broken by twisting the said tongue.

7. A safety razor and blade combination including a razor having cooperating blade-clamping members provided at one end with wedge-shaped tie-breaking device, together with a slotted blade having a slot-closing tie at one end located in position to be broken out of the blade by the tie-breaking device of the razor when the blade is presented endwise between the said clamping members.

8. A safety razor and blade combination including a razor having cooperating blade-clamping members arranged to be separated to provide a blade-passage between them, and a tie breaker located in the blade passage at one end of the razor, together with a slotted blade having a tie across one end of its slot located in position to be broken by encountering said tie-breaker when presented endwise between the said clamping members.

9. A safety razor and blade combination including a razor having cooperating blade-clamping members connected to provide a blade passage between them, and a tie breaker having an inclined face, together with a slotted blade having a tie across one end of its slot, the tie having a projection so located as to encounter the said inclined face, whereby the tie may be broken out by a twisting movement.

MEYER J. SHNITZLER.
